UNITED STATES PATENT OFFICE.

WILLIAM A. MINOR, OF ROCHESTER, NEW YORK, ASSIGNOR TO LUITWIELER PUMP-
ING ENGINE COMPANY, OF ROCHESTER, NEW YORK, A CORPORATION OF NEW
YORK.

PACKING.

Application filed November 29, 1924. Serial No. 752,963.

To all whom it may concern:

Be it known that I, WILLIAM A. MINOR, a citizen of the United States, and resident of Rochester, in the county of Monroe and 5 State of New York, have invented certain new and useful Improvements in Packing, of which the following is a specification.

The present invention relates to packing and to a method of making the same. An 10 object of the invention is to produce a more serviceable packing designed for pump pistons and other structures where the packing is carried by a moving part or has a moving part co-operating therewith. A further 15 object of the invention is to provide a packing which can be stored in stock previously to being used without losing its shape.

To these and other ends, the invention 20 consists of certain parts and combinations of parts, all of which will be hereinafter described: the novel features being pointed out in the appended claims.

In the drawings:

The figure is a sectional view of a cupped 25 leather for pump pistons constructed in accordance with this invention.

In carrying out the invention the leather is first treated to soften the fibers, and to 30 soften and destroy any grease or tallow which may be present in the leather. This is accomplished preferably by the immersion of the leather in hot water which has a temperature varying with different types of leather but sufficient to perform the 35 results set forth. Any other agent may be used for softening the leather and destroying the grease or tallow so long as the agent will perform the functions without adding any material that will fill the pores of the 40 leather.

After the leather is softened and while in this condition, it is molded into the desired shape and baked or heated to a 45 temperature just under the burning point of the particular leather used. This evaporates the water or liquid in the leather and causes the leather to take a permanent set, the fibers adjusting themselves to their new 50 positions. If leather is heated with the grease and tallow therein, the fibers will merely stretch and do not take permanent set, so that after being removed from the mold, the leather will gradually resume its former shape.

After the molding process, the leather is 55 filled with a suitable hardening and strengthening wax, such for instance as chrome sole stuffing. This hardening and strengthening wax is first dissolved, preferably without the use of heat, in a suitable agent such, for instance, as carbon tetrachloride. The leather is then dipped or immersed in this solution and the solution penetrates the pores of the packing carrying the wax therein without the use of 60 heat. The solvent is then permitted to evaporate, leaving the leather perfectly filled or stuffed with the wax.

A packing produced according to this 65 invention will maintain its shape making it possible for jobbers or dealers to furnish immediately repairs to pump operators, a result which has not been possible before, due to the fact that molded packing when held in stock will after a time lose its shape. 70 The filler tends to act as a lubricant for the part over which the packing moves thereby increasing the efficiency of the packing. All pores of the packing are closed whereby 75 the packing is strengthened and water under pressure is prevented from penetrating and destroying the packing. A packing made in accordance with this invention is hardened to such an extent that it provides 80 an increased resistance to sand, which in deep well pumps has heretofore rapidly 85 destroyed the packing.

What I claim as my invention and desire to secure by Letters Patent is:

1. A leather packing in molded form 90 having the tallow and grease removed and stuffed with a hardening and strengthening wax.

2. The process of treating leather packings which consists in removing the tallow 95 or grease from the leather, molding the leather into the desired shape under the action of heat, and filling the pores of the molded packing with a wax containing solution having a volatile solvent which 100 will not destroy the molded shape.

3. The process of treating molded leather packings which consists in immersing the 105 molded packing in a cool solution containing wax and a volatile solvent, to cause the wax to be carried into the pores without heat and the solvent to volatilize and leave the wax in the pores of the packing.

4. The process of making leather packing which consists in removing the tallow and grease from the leather with an agent which will soften the leather, molding the packing while in a soft state, and heating it while it is in the mold to cause the fibers of the leather to take a permanent set.
5. The process of making leather packing which consists in removing the tallow

and grease from the leather with an agent ¹⁰ which will soften the leather, molding the packing while in a soft state, and heating it while it is in the mold to cause the fibers of the leather to take a permanent set and thereafter filling the packing with a wax ¹⁵ without destroying the molded shape of the packing.

WILLIAM A. MINOR.
